BOTTLE CAP CLOSURE

George W. Alexander, Boston, Mass., assignor to
Thorndike Engineering Corporation, Cam-
bridge, Mass.

Application February 24, 1937, Serial No. 127,445

1 Claim. (Cl. 215—46)

My present invention relates to bottle closures, and more particularly to the crimped cap commonly used for beer bottles and the like.

The principal object of my invention, is to provide an improved bottle cap closure of the class described which may be easily removed without the use of special tools;

Another object is to provide an improved cap closure having certain weakened portions adjacent the periphery of the cap blank which will yield to light pressure.

Other objects and novel features comprising the construction and operation of the invention will be apparent as the description of the same progresses.

In the drawing illustrating the preferred embodiment of my invention:

Fig. 1 illustrates a sheet-metal blank from which caps of the class described may be made; Fig. 2 shows a second step in the preparation of the blank prior to crimping the edges of the same;

Fig. 3 shows a typical cross-section taken through the cap after it has been formed, this cross-section being taken on the line indicated at 3—3 in Fig. 2 and is increased in scale to about double size;

Fig. 4 is a plan view of a completely formed cap particularly showing one of the weakened sections having been turned up, as is the case when the cap is removed, and

Fig. 5 is a cross-section taken on the line 5—5 of Fig. 4, particularly showing the weakened material at this point, and the same being greatly exaggerated.

Referring more in detail to the drawing, the reference numeral 10 indicates a blank disc of metal from which my improved cap may be made. At certain points about the periphery, and extending inwardly toward the center, I have indicated, by the numeral 11, certain areas representing thin portions. There may be any num-

ber of these thinned places desired. These thinned areas are formed in any manner found consistent with shop practice, as by means of dies etc. The degree of thinning to which the metal is subjected may vary under certain requirements.

At Fig. 5, I have made an attempt to show an exaggerated cross-section in which I have indicated at 12 the normal thickness of the metal surrounding these portions 11, the material shown in cross-section at 13 being the actual metal after the area has been thinned.

At Fig. 4 I have shown one of the metal closures after it has been crimped, and particularly showing one of the thinned areas having been lifted, at 14, and turned back. Each of the other areas 11 may be treated in a like manner.

Normally, a cap of the class referred to is crimped over the raised lip of a bottle neck and requires considerable force to remove the same with bottle cap openers of various designs. In my improved cap, I have thinned the metal adjacent the periphery of the disc from which the cap is made to a point where it is very easy to rip the metal along the edges from the periphery of the cap outlining the thinned portion. Any common tool or even the finger-nail of the operator will supply the required force to do this. The segment 14 may then be folded back, as shown at 14, in Figs. 3 and 4. If desired indicating marks 15 may be placed on the outside of the cap to indicate the planes in which these weakened areas lie.

Having thus described my invention, what I claim as new is:

An improved bottle closure comprising a top portion and crimped side flange, a plurality of crimps on said side flange having a thickness of a lesser gauge than the surrounding material comprising the rest of said closure.

GEORGE W. ALEXANDER.
